UNITED STATES PATENT OFFICE.

JOHN JERNBERG, OF WORCESTER, MASSACHUSETTS.

TEMPERATURE-REGULATOR.

SPECIFICATION forming part of Letters Patent No. 561,401, dated June 2, 1896.

Application filed May 18, 1895. Serial No. 549,759. (No model.)

To all whom it may concern:

Be it known that I, JOHN JERNBERG, a citizen of the United States, residing at Worcester, in the county of Worcester and State of Massachusetts, have invented a new and useful Improvement in Temperature-Regulators, of which the following is a specification.

The object of my invention is to provide a simple, efficient, and durable form of temperature-regulating device; and the especial object of my invention is to provide a hot-water circulatory system and a temperature-regulating device which is especially applicable to incubators.

15 To these ends my invention consists of the parts and combinations of parts, as herein-after described, and more particularly pointed out in the claims at the end of this specification.

20 In the accompanying drawings, Figure 1 is a top plan view of an incubator constructed according to my invention, and Fig. 2 is a longitudinal sectional view of the same.

25 Referring to the drawings and in detail, A designates the outside casing or shell of an incubator, and B designates the egg-chamber.

Fastened upon and carried by a bracket 10 at one end of the incubator I provide a water-heater C. The heater C is substantially cylindrical in form and is provided with a central flue 11, having four perpendicular branch or heating flues 12. Connected with the central flue 11 below the body of the heater C is an exhaust-flue 13. Heat may be supplied to 35 these flues by means of an ordinary lamp D or other suitable heating device.

The heated water from the top of the heater C flows through the supply-pipe 14, and the water as it is cooled is returned to the bottom 40 of the heater C through a return-pipe, as 15.

Connected with and leading from the casting A, I provide a vertical pipe 16, which is connected with a pivoted movable vessel E by means of a flexible section of pipe 17. The pivoted or movable vessel E is mounted on the top of the casing A in a bracket 18 by means of suitable center-screws 19, as shown. Extending from one end of the movable vessel E is a hook 20, which engages with a link 21, supported on one end of a lever 22. The lever 22 is pivotally supported in a bracket 23 by means of center-screws 24, and in order to control

and regulate the motion of the parts I may provide the lever 22 with an adjustable counterweight 26, and the bracket 23 may be provided with adjustable stops 25, as shown. At its opposite end the lever 22 is connected to a perforated vertically-movable damper F by means of a rod 27.

The damper F is mounted in the central flue 11 and is provided near its upper end with a series of perforations corresponding with the heating-flues 12. When in its lowest position, the damper F will extend down so as to cut off the exhaust-flue 13, causing the heat 65 to pass through the vertical heating-flues 12. When the damper F is raised, the heating-flues 12 will be cut off from the central flue 11 and the heat will be deflected through the exhaust-flue 13.

70 The operation of my improved temperature-regulating device may be briefly described as follows: When the temperature rises above the desired point, the water in the circulatory system will expand, and the weight of the 75 water in the movable vessel E increasing the vessel E will move downward and through its connections will raise the damper F, thus deflecting the heat from the flues 12 into the exhaust-flue 13, allowing the temperature of 80 the water in the circulatory system to fall. When the water again becomes cooler and contracts, the weight of water in the movable vessel E will decrease, the damper F will fall, and the heat will again be allowed to pass 85 through the heating-flues 12.

In some cases, in order to prevent the evaporation of the water contained in the circulatory system, the top of the pipe 16 and of the movable vessel E may be closed, and where 90 this construction is adopted a puppet-valve or other safety device for preventing abnormal pressures should be provided.

I am aware that other changes in the construction of the device may be made by those 95 who are skilled in the art, and I do not wish, therefore, to be limited to the construction which I have shown and described; but

What I do claim, and desire to secure by Letters Patent of the United States, is— 100

1. The combination of an incubator, a hot-water circulatory system comprising circulatory-passages, a hot-water heater having an exhaust-flue, a supply-flue, and heating-flues

leading from said supply-flue, a source of heat, a movable damper having perforations arranged to coöperate with the heating-flues, and means for automatically operating said 5 damper to positively cut off or close either the heating-flues or the exhaust-flue, substantially as described.

2. The combination of an incubator, a hot-water circulatory system for said incubator, comprising a water-heater having a central supply-flue, heating-flues and an exhaust-flue leading from said central flue, a damper mounted in said central flue having perforations arranged to coöperate with said heating-

flues, said damper being arranged to positively 15 cut off said heating-flues when in its elevated position, and means controlled by the expansion of the water in the circulatory system for automatically operating said damper, substantially as described.

20 In testimony whereof I have hereunto set my hand in the presence of two subscribing witnesses.

JOHN JERNBERG.
